1318, 1319, 1319, 1320, 1321, 1322, 1323, 1324, 1325, 1326, 1327, 1328, 1329, 1329, 1330, 1331, 1332, 1333, 1334, 1335, 1336, 1337, 1338, 1339, 1339, 1340, 1341, 1342, 1343, 1344, 1345, 1346, 1347, 1348, 1349, 1349, 1350, 1351, 1352, 1353, 1354, 1355, 1356, 1357, 1358, 1359, 1359, 1360, 1361, 1362, 1363, 1364, 1365, 1366, 1367, 1368, 1369, 1369, 1370, 1371, 1372, 1373, 1374, 1375, 1376, 1377, 1378, 1379, 1379, 1380, 1381, 1382, 1383, 1384, 1385, 1386, 1387, 1388, 1389, 1389, 1390, 1391, 1392, 1393, 1394, 1395, 1396, 1397, 1398, 1398, 1399, 1399, 1400, 1401, 1402, 1403, 1404, 1405, 1406, 1407, 1408, 1409, 1409, 1410, 1411, 1412, 1413, 1414, 1415, 1416, 1417, 1418, 1419, 1419, 1420, 1421, 1422, 1423, 1424, 1425, 1426, 1427, 1428, 1429, 1429, 1430, 1431, 1432, 1433, 1434, 1435, 1436, 1437, 1438, 1439, 1439, 1440, 1441, 1442, 1443, 1444, 1445, 1446, 1447, 1448, 1449, 1449, 1450, 1451, 1452, 1453, 1454, 1455, 1456, 1457, 1458, 1459, 1459, 1460, 1461, 1462, 1463, 1464, 1465, 1466, 1467, 1468, 1469, 1469, 1470, 1471, 1472, 1473, 1474, 1475, 1476, 1477, 1478, 1479, 1479, 1480, 1481, 1482, 1483, 1484, 1485, 1486, 1487, 1488, 1489, 1489, 1490, 1491, 1492, 1493, 1494, 1495, 1496, 1497, 1498, 1498, 1499, 1499, 1500, 1501, 1502, 1503, 1504, 1505, 1506, 1507, 1508, 1509, 1509, 1510, 1511, 1512, 1513, 1514, 1515, 1516, 1517, 1518, 1519, 1519, 1520, 1521, 1522, 1523, 1524, 1525, 1526, 1527, 1528, 1529, 1529, 1530, 1531, 1532, 1533, 1534, 1535, 1536, 1537, 1538, 1539, 1539, 1540, 1541, 1542, 1543, 1544, 1545, 1546, 1547, 1548, 1549, 1549, 1550, 1551, 1552, 1553, 1554, 1555, 1556, 1557, 1558, 1559, 1559, 1560, 1561, 1562, 1563, 1564, 1565, 1566, 1567, 1568, 1569, 1569, 1570, 1571, 1572, 1573, 1574, 1575, 1576, 1577, 1578, 1579, 1579, 1580, 1581, 1582, 1583, 1584, 1585, 1586, 1587, 1588, 1589, 1589, 1590, 1591, 1592, 1593, 1594, 1595, 1596, 1597, 1598, 1598, 1599, 1599, 1600, 1601, 1602, 1603, 1604, 1605, 1606, 1607, 1608, 1609, 1609, 1610, 1611, 1612, 1613, 1614, 1615, 1616, 1617, 1618, 1619, 1619, 1620, 1621, 1622, 1623, 1624, 1625, 1626, 1627, 1628, 1629, 1629, 1630, 1631, 1632, 1633, 1634, 1635, 1636, 1637, 1638, 1639, 1639, 1640, 1641, 1642, 1643, 1644, 1645, 1646, 1647, 1648, 1649, 1649, 1650, 1651, 1652, 1653, 1654, 1655, 1656, 1657, 1658, 1659, 1659, 1660, 1661, 1662, 1663, 1664, 1665, 1666, 1667, 1668, 1669, 1669, 1670, 1671, 1672, 1673, 1674, 1675, 1676, 1677, 1678, 1679, 1679, 1680, 1681, 1682, 1683, 1684, 1685, 1686, 1687, 1688, 1689, 1689, 1690, 1691, 1692, 1693, 1694, 1695, 1696, 1697, 1698, 1698, 1699, 1699, 1700, 1701, 1702, 1703, 1704, 1705, 1706, 1707, 1708, 1709, 1709, 1710, 1711, 1712, 1713, 1714, 1715, 1716, 1717, 1718, 1719, 1719, 1720, 1721, 1722, 1723, 1724, 1725, 1726, 1727, 1728, 1729, 1729, 1730, 1731, 1732, 1733, 1734, 1735, 1736, 1737, 1738, 1739, 1739, 1740, 1741, 1742, 1743, 1744, 1745, 1746, 1747, 1748, 1749, 1749, 1750, 1751, 1752, 1753, 1754, 1755, 1756, 1757, 1758, 1759, 1759, 1760, 1761, 1762, 1763, 1764, 1765, 1766, 1767, 1768, 1769, 1769, 1770, 1771, 1772, 1773, 1774, 1775, 1776, 1777, 1778, 1779, 1779, 1780, 1781, 1782, 1783, 1784, 1785, 1786, 1787, 1788, 1789, 1789, 1790, 1791, 1792, 1793, 1794, 1795, 1796, 1797, 1798, 1798, 1799, 1799, 1800, 1801, 1802, 1803, 1804, 1805, 1806, 1807, 1808, 1809, 1809, 1810, 1811, 1812, 1813, 1814, 1815, 1816, 1817, 1818, 1819, 1819, 1820, 1821, 1822, 1823, 1824, 1825, 1826, 1827, 1828, 1829, 1829, 1830, 1831, 1832, 1833, 1834, 1835, 1836, 1837, 1838, 1839, 1839, 1840, 1841, 1842, 1843, 1844, 1845, 1846, 1847, 1848, 1849, 1849, 1850, 1851, 1852, 1853, 1854, 1855, 1856, 1857, 1858, 1859, 1859, 1860, 1861, 1862, 1863, 1864, 1865, 1866, 1867, 1868, 1869, 1869, 1870, 1871, 1872, 1873, 1874, 1875, 1876, 1877, 1878, 1879, 1879, 1880, 1881, 1882, 1883, 1884, 1885, 1886, 1887, 1888, 1889, 1889, 1890, 1891, 1892, 1893, 1894, 1895, 1896, 1897, 1898, 1898, 1899, 1899, 1900, 1901, 1902, 1903, 1904, 1905, 1906, 1907, 1908, 1909, 1909, 1910, 1911, 1912, 1913, 1914, 1915, 1916, 1917, 1918, 1919, 1919, 1920, 1921, 1922, 1923, 1924, 1925, 1926, 1927, 1928, 1929, 1929, 1930, 1931, 1932, 1933, 1934, 1935, 1936, 1937, 1938, 1939, 1939, 1940, 1941, 1942, 1943, 1944, 1945, 1946, 1947, 1948, 1949, 1949, 1950, 1951, 1952, 1953, 1954, 1955, 1956, 1957, 1958, 1959, 1959, 1960, 1961, 1962, 1963, 1964, 1965, 1966, 1967, 1968, 1969, 1969, 1970, 1971, 1972, 1973, 1974, 1975, 1976, 1977, 1978, 1979, 1979, 1980, 1981, 1982, 1983, 1984, 1985, 1986, 1987, 1988, 1989, 1989, 1990, 1991, 1992, 1993, 1994, 1995, 1996, 1997, 1998, 1998, 1999, 1999, 2000, 2001, 2002, 2003, 2004, 2005, 2006, 2007, 2008, 2009, 2009, 2010, 2011, 2012, 2013, 2014, 2015, 2016, 2017, 2018, 2019, 2019, 2020, 2021, 2022, 2023, 2024, 2025, 2026, 2027, 2028, 2029, 2029, 2030, 2031, 2032, 2033, 2034, 2035, 2036, 2037, 2038, 2039, 2039, 2040, 2041, 2042, 2043, 2044, 2045, 2046, 2047, 2048, 2049, 2049, 2050, 2051, 2052, 2053, 2054, 2055, 2056, 2057, 2058, 2059, 2059, 2060, UNITED STATES PATENT OFFICE

CONRAD WISSEMAN, OF GELSENKIRCHEN, GERMANY.

UNDERGROUND MINING.

1,201,537.

Specification of Letters Patent. Patented Oct. 17, 1916.

Application filed October 15, 1913. Serial No. 795,239.

To all whom it may concern:

Be it known that I, CONRAD WISSEMAN, a subject of the King of Prussia, residing at 33 Hochstrasse, Gelsenkirchen, in the German Empire, have invented new and useful Improvements in Underground Mining, of which the following is a specification.

My invention relates to mining machinery, especially constructed for mining coal by 10 entirely mechanical power.

Hitherto, mining and subsequent loading of coal had to be done mainly by manual labor. Workmen's wages amounted to two-thirds of the working expenses, therefore, it 15 is obvious that a displacement of manual labor by machine work would effect an important economy in the working of a coal field.

It is the object of my present invention 20 to provide machinery by means of which mining of a coal field and loading of the coal into buggies may be carried on entirely by mechanical means.

In the accompanying drawings forming a 25 part of this specification, an embodiment of my invention is shown by way of example.

Figure 1 represents an inclined vertical section of a coal mine showing a plan view of my machinery in working position. Fig. 30 2 is a modified sectional side view of Fig. 1 showing the conveyer belt replaced by a chute. Fig. 3 is a modification of the lower end of Fig. 2 in accordance with a coal seam having an inclination of less than 30 degrees.

Fig. 4 is a rear view partly in cross section, on an enlarged scale of the coal cutting machine and the frame work connected thereto with some of the parts omitted. Fig. 5 is an enlarged sectional view of the foot of the 35 column 15 shown in Fig. 4. Fig. 6 is a sectional plan view on the line M—N in Fig. 5.

Fig. 7 is a plan view of the lower part of the machinery illustrated in Fig. 1. Fig. 8 is a vertical section on line 8—8 Fig. 7. Fig. 45 9 is a side view on an enlarged scale of the upper part of the machinery. Fig. 10 is a plan view of a portion of Fig. 9. Fig. 11 is a cross section on line 11—11 Fig. 4. Fig. 12 is a face view of said automatic coal cutting machine, and Fig. 13 a sectional view 50 on the line Q—R in Fig. 12.

The construction, and the mode of operation, of the machinery for underground mining shall now be described with reference to 55 the drawings.

The extension of the coal bed of a coal

work will generally keep within the following measurements; inclined length of seam face: 200 feet to 400 feet; level width of seam: 600 feet to 1000 feet. According to 60 my invention two rows of mine columns are placed along the face of the seam extending between the air head and the water level or rolley-way, the columns are rigidly connected, one with the other, by means of a frame 65 work, and they support on their heads small iron girders that carry sheeting boards which are to take the place of caps. The heads of the columns are pressed against the roof of the mine by means of mechanically 70 operated screws. The entire frame work is carried on wheels which are rotated from a power driven shaft. Thus the whole frame work may be moved sidewise in the direction of the strike (see Figs. 1 and 2). 75

In the upper gangway, or air head, strong mining columns 2 are put up, on which is hanging by means of rods 3 a longitudinally extending girder 4. On truckles 5 arranged to run along the girder 4, the whole frame work is suspended and may be moved sideways in the direction of the strike while the work of mining is advancing. At the head of the frame work a drum 7 driven by the motor 6 is mounted, such motor being 80 preferably a compressed air motor or a fire damp-proof benzol motor. Around the drum 7 is passed a wire rope on the one side of which the automatically working coal cutting machine 8 is suspended while 85 on the other side the rope is connected to a counter-weight 9 provided with truckles that run upon rails 159 as shown in Fig. 4. The rails are mounted on lateral arms projecting from the frame work. On the row 90 of columns next to the face of the seams, and fastened to these columns, a U-shaped girder 17 is arranged to serve as a guide for the automatic coal cutting machine shown in Fig. 4 that works along the face of the seam cutting off a slice in the whole thickness of the stratum. The coals broken are moved by the cutting machine over plate 34 slightly inclined toward suitable delivery means such as a traveling belt 33 that carries the coals down on to the coal spout 61 wherefrom the coals are loaded into trucks 95 moving on the floor of the rolleyway.

At the lower end of the frame work, or at any other suitable place, is arranged the 100 motor 11 which can be used to drive either the drum 12 for moving the traveling belt

33, or the shafts 21, 21^a that cause, when rotated, the columns to extend or contract, or the shafts 40, 40^a that communicate their rotation to the wheels 39 carrying the frame 5 work when the latter is to be moved sidewise in the line of the strike.

To put the coal cutting machine 8 into working position, the lower corner portion of the coal bed is hewn out by hand, and 10 the roof of the chamber thus formed is secured by means of columns and timbers.

The mode of operation will now be as follows: The coal cutting machine 8 is set to the lower end 13 in Fig. 1 from where 15 it travels along the face of the seam severing a coal slice of a thickness of more than one foot whereupon the cutting machine is let down again to the chamber 13. By motor power the screw heads of the columns of 20 the frame work are lowered, and the latter moved on sidewise also by motor power. In order to secure the frame work again between roof and floor of the mine the column heads are made to extend by applying 25 motor power to the corresponding shafts and connections. The work of coal cutting may then be proceeded with. The buggies can be loaded successively and may be moved on to the colliery shaft in trains instead 30 of singly, either by horses or by means of an engine.

As already mentioned the coal cutting machine 8 indicated in Fig. 1 and shown in detail in a rear view in Fig. 4, is being drawn 35 over the face of the coal deposit and thereby undercut, and subsequently breaks off, a slice of the seam in the whole thickness of the bed. The columns 15, 15^a arranged along the face of the coal bed may be exchanged, and substituted by others to accord 40 with the thickness of the coal stratum to be treated; thus beds of any thickness varying between 1½ feet and 6 feet can be worked with this machinery.

45 The U-shaped irons 17 guiding the cutting machine by means of truckles 18 18 and rod 19^a, are mounted in brackets fastened to the columns 15 by means of collars 16 that carry on the opposite side bracket bearings 20 for 50 the shaft 21 having worms that engage the worm wheels 22 carried on the heads of the columns 15, and kept in position by sleeves 24. The worm wheel is threaded to receive the screw spindle 23 that extends into the 55 tubular column 15. Above the screw spindle 23 are supported, on the head plate 25, girders 26 to which are connected cross-beams 27 having diagonal stays made of flat-irons. Upon the girders 27 sheeting 60 boards are placed covering more or less of the surface of the roof; they are kept in proper position by means of elastic clamps 29. Small stones breaking off the roof slide off the smooth and slightly curved surface 65 of the sheeting boards, or slip down between

them. Should a larger stone detach from the roof in that case the boards can be moved aside in order that the stone may be removed.

Similar collars 16^a are provided on the 70 second row of columns 15^a to support the bracket bearings 20^a for the shaft 21^a arranged to communicate the rotating movement to the screw spindles 23^a.

By putting the shafts 21, 21^a into motion 75 the spindles 23, 23^a are caused to extend or to go down, thereby pressing the roofing structure against the roof of the mine, or lowering it down.

On the lower end of the columns 15 collars 30 are arranged fitting loosely around the columns, as shown in Figs. 5 and 6. On the side facing the seam axles 31, 31 are connected to the collars 30, on which axles small rollers 32 are mounted that support 85 and guide the traveling belt 33, as shown in Fig. 4. Between the traveling belt 33 and the coal cutting machine an inclined plate 34 is provided that is supported on wheels 35 and discharges coal moved along its 90 surface by a power operated shoveling board, on to the belt 33 to carry the coal down into the coal spout from where it is loaded into trucks running on the floor of the rrolleyway as shown in Figs. 3, and 8. 95

Within the lower part of each of the tubular columns 15 and 15^a and around a pin 37 a helical spring 36 is arranged which rests on a yoke made integral with the pin, and which bears against a ring 38 kept in 100 position by bolts screwed through the wall of the column. The yoke of pin 37 is recessed to receive worm 42 and worm wheel 41, the latter being mounted on the axle of the wheels 39, 39. The shaft 49 on which 105 the worm 42 is mounted is rotated by the worm gearing 43, 43^a from the shaft 40. This shaft drives only column 15, while column 15^a is pulled along by the connecting frame work 27.

When the shafts 21, 21^a are operated to extend the screw spindles 23, 23^a of the columns 15, 15^a the helical springs 36 are being compressed until the ends of the columns touch the floor of the mine. On reversing the direction of revolution of shafts 21, 21^a, the springs 36 expand as soon as the screw spindles 23, 23^a are turned sufficiently to allow the columns 15 and 15^a to raise 115 themselves from the ground, and therewith the whole frame work, which can then be wheeled on, in the line of strike, by putting into operation the shaft 40. The revolving movement of the latter will then be transmitted to the wheels 39 over the two worm gears 43^a, 43 and 42, 41 causing the frame work to move to the new working position where the extending columns are again propped up between mining roof and floor.

On the side of the frame work, opposite to the coal bed and near the lower end, the motor 11 may be placed as illustrated in Fig. 7 in a frame 51 that permits of turning the motor on an axle in such a way as to insure its vertical position whatever the inclination of the coal bed may be like. The motor 6 on the head of the frame work is mounted after the same principle.

10 By means of shaft 52 the motor drives the gear wheel 54 that engages the gear wheel 55 over which the rotation is imparted to the square shaft 56 that can be longitudinally moved in order to cause the gear wheel 57, unmovingly mounted on it, to engage other gear wheels mounted on parallelly disposed shafts. On moving the gear wheel 57 into position I engagement with gear wheel 58 is effected which imparts 20 rotation to drum 12 operating the traveling belt 33 that carries the coals as gained into trucks. If gear wheel 57 is moved into position II the shaft 56 is running free, while in the position III the gear wheel 57 engages 25 gear wheel 62 and transmits its rotation by means of the bevel gear 63, 64 to the shaft 40^a connected by a second bevel gear 75, 76 to the shaft 40 which effects a sidewise shifting of the frame work. On moving 30 gear wheel 57 into the position IV the shaft 56 is again running free. In the position V the gear wheel 57 engages gear wheel 65 that is connected through gear 68, 69, intermediate shafts 70, 70^a, bevel gears 71, 72; 35 74, 73 and 74^a, 73^a, to shafts 21 and 21^a. The movement of these latter parts is reversed in position VI by means of an intermediate gear wheel 66 inserted between the gear wheels 57 and 67. While the columns 40 15, 15^a will be extended when gear wheel 57 is moved into position V the opposite operation will be effected if gear wheel 57 is advanced into position VI; the latter operation resulting in lowering the screw heads 45 of columns 15, 15^a, is carried out in less time owing to the larger ratio of transmission obtained in position VI.

In order to permit a rotation of gears 62 and 65 independent of each other, the shaft 50 supporting the same is made in two sections as clearly illustrated in Fig. 7.

The mode of operation of the mechanism as described is as follows. Supposing the coal cutting machine is at work, the gear 55 wheel 57 will then be in position I engaging the gear wheel 58 and thereby causing the traveling belt 33 to move. After the coal cutting machine has undercut and broken off a slice of coal along the entire length of 60 the seam and has been returned into its lowermost position, the gear wheel 57 is made to occupy the position VI in which it revolves, in backward direction, the shafts 21, 21^a that now lower the heads of columns 65 15, 15^a. The springs 36 come into operation

and lift the columns 15, 15^a from the floor. On shifting gear wheel 57 into position III power of rotation is imparted to the shaft 40 whereupon the whole frame work is wheeled on sidewise into its new working position. Passing the position IV the gear wheel 57 is set to work in position V thereby causing columns 15, 15^a to extend: the springs 36 are compressed again until the 70 columns rest firmly on the mining floor and the frame work affords sufficient hold for the traveling belt and the guidance of the coal cutting machine. The gear wheel 57 is now to be shifted into position I, that starts the cutting work anew.

These different operations may be carried out by means of the motor 11 by a single operator in few minutes' time. Returning the coal cutting machine into the starting position after having traveled along the 80 face of the seam, takes only one or two minutes' time, hence this new machinery works almost continuously.

At the upper end of the frame work the 90 drum 7 is arranged which drum is driven from the motor 6 through bevel gear 81, 82, and two successive worm gears 83 and 84. The motor 6 is mounted within a frame 200^a turning on shaft 200 and adjustably secured to segments 202 by means of screws 201, 201^a. For stretching the traveling belt the stretching car 85 is provided carrying on an axle the drum 86 around which the traveling belt passes. Before the frame work is loosened and moved sidewise the 100 stretching device 87 must be undone as otherwise the frame work would be spoiled by bending.

Between the flat-iron trellis-work connecting the feet of the columns boards 240 (Fig. 9) are inserted and fastened in such 105 a manner that they may be turned around their front edge and adjusted in accordance with the dip of the coal bed. In this way a flight of steps is formed between the 110 two rows of columns for the engine-men to control the whole machinery.

The coal cutting machine as indicated in Figs. 1 and 2 by reference numeral 8 will now be described with reference to the Figs. 115 11, 12 and 13.

As is shown in Figs. 4 and 11 near the column heads of the first row U-shaped irons 17 are provided on the inside of which guide rollers 18, 19 rotatably mounted on the flat iron piece 90, are made to run guiding the coal cutting machine by means of the adjustable rods 19^a, 19^a. One of these rods is fastened to the base of the machine while the other one is rigidly connected to the 120 curved arm 91 projecting from the base of the machine and terminating in a ring through which the end of the steel rope is wound that passes around the drive drum 7 to the counter-weight 9.

The coal cutting machine consists of a front part working in the coal bed, and a rear part containing the driving mechanism. A common driving shaft is provided 5 that is coupled by known means to the axle of a motor not shown in Fig. 11 but indicated in Fig. 1. The motor is arranged in the rear of the coal cutting machine and the above described coupling device is such 10 as to permit the cylinders of the motor always to occupy a vertical position, whatever the inclination of the coal seam may be like.

The front part of the coal cutting machine 15 contains the borers 93 arranged parallelly in a vertical plane and spaced about $1\frac{1}{2}$ feet apart. The wedge-shaped casing 94 of the bore shafts 93^a assists plates 95, 95^a, 95^b, 95^c to break off the undercut coal under the pressure exerted by the slowly advancing machine. This pressure is very considerable owing to the large ratio 20 of power transmission. The oscillating plates 95, 95^a, 95^b, 95^c tapering toward the forward end are inserted into the bore holes 25 to break up the undercut slice of coal and throw the coal off sidewise.

The different parts composing the machine are mounted on a framework consisting 30 of a number of parts, designated by the numerals 96, 96^a, 96^b, 96^c, all disposed in a common vertical plane. These individual parts can be variably spaced apart so that the machine may be adapted to varying coal 35 seam thicknesses. Within short distances the thickness of the seam varies not considerably; perhaps from 10 to 20 per cent. only. In order to gain the coal pure it is necessary to adapt the machine to varying thicknesses 40 of the seam. This may be done with the construction illustrated in Fig. 12.

To the lowermost plate forming a part of the machine framework the plate 150 is secured by screws. In recesses of this plate a second plate 151 is made to slide, and is secured to the uppermost plate 96^c by screws. For the intermediate plates 96^a, 96^b, to slide in, the plate 151 is provided with a suitable recess holding and guiding these plates. Further guiding means are provided by the guiding bars 152, 152^a. The different plates 50 may be moved together, or apart, by means of screw spindles 153, 153^a each one composed of several parts provided with a screw thread of different pitch, the pitch of successive spindle parts increasing relatively with the distance of the respective plates from the uppermost plate 96^c. The pitch of each spindle part must be such that the 55 spaces between the individual plates when the latter are being moved together or apart, by means of spindles 153, 153^a remain almost equal with regard to each other. The spindles 153, 153^a turn in nuts bracketed to 60 the plates, and are mounted at their upper

ends, in bearings secured to plate 96^c. They are rotated simultaneously by means of hand wheel 158, shaft 157 and worm gear 156. By this construction the machine can be adapted to all requirements. 70

The machine is guided along the face of the coal bed by wheels 145, 145, running in the grooves made by the borers 93, and is carried on wheels 101, 102 and 103. The former two wheels take up almost all the 75 weight of the machine, and are power driven for moving the machine forward. They are running behind small way clearers in the lowermost bore grooves made by the last and the present cutting shift. For that purpose the lowermost borer is not arranged in the same plane with the others but retracted somewhat as may be seen in Fig. 13. The running wheel 103 in front of the drive 80 wheels 101, 102 is adapted to be used for steering the machine in a vertical plane which steering operation can be carried out by means of hand wheel 106, shaft 106^a, and worm gear 105. By raising, or lowering, steering wheel 103 the machine is made to 85 follow any irregularities in the dip of the coal bed.

With soft and easily breaking coal a thicker slice may be cut off the seam. To adjust the machine to requirements of this 90 kind the guide rods 19^a, and the axles of the wheels 101, 102, are adapted to be extended as shown in Figs. 11 and 12.

When the machine is in operation the rotation of shaft 92 is transmitted to shaft 110 100 by means of bevel gear wheels 107, 107^a, intermediate shaft 108, and worm gear 109. Shaft 110 carries a worm 111 engaging the worm wheel 112 mounted on the axle of the wheels 101, 102. The shaft 110 is adapted 105 to be displaced, thereby disengaging worm gears 109 and 111; the machine can then be freely moved. If the machine is to be wheeled backward the shaft 92 is longitudinally shifted toward the rear of the machine 110 and the shaft 115 is longitudinally moved 115 forward till the worm 116 engages the worm wheel 117 mounted on the axle of wheels 101, 102. In this position the gear wheel 113 engages gear wheel 114 and transmits 115 the rotation of the power driven shaft 92 to shaft 115, worm gear 116, 117, and wheels 101, 102 whereby the coal cutting machine 120 is moved in backward direction at a greater speed than in forward direction owing to 125 the different ratio of transmission. Through shifting the shaft 92 longitudinally for this purpose the gear wheels 123 and 124 have become disengaged, hence the cutting tools 125 are not working during this backward movement of the latter.

Besides the gear wheels mentioned there is a further bevel gear wheel provided on shaft 92 engaging the bevel gear wheel 120 130 for the following purpose: With a coal bed

having a large angle of inclination with the horizontal the coal broken may easily be pushed by the board 119 over the inclined plate 34, on to the traveling belt 33, or on to 5 a coal chute that may be used instead of a traveling belt, while the machine is advancing. However with an almost horizontally disposed coal bed it is necessary to impart to the board 119 a shoveling movement. This 10 is effected from the shaft 92 by means of bevel gear 118, 120, two worm gears 121, 121^a, and two connecting rods 121^b. In performing the shoveling movements the board is guided at 122 in a known manner. By 15 these shoveling movements of board 119 the coals are transferred to the conveyer 33.

At the front end there is fixed to the shaft 92 the gear wheel 123 engaging gear wheel 124 for the purpose of driving the cutting 20 tools. At the side of gear wheel 124, on the same shaft therewith, a bevel gear wheel 125 is mounted engaging the bevel gear wheel 125^a mounted on the vertically disposed shaft 126 which latter is composed of parts rendering the shaft extensible for the reason described in connection with the screw spindles 153, 153^a. On the shaft 116 further bevel gear wheels are provided meshing with similar bevel gear wheels mounted on the shafts 25 128, 128^a, 128^b, 128^c, which latter shafts as well as the shaft 134, are connected by universal joints 130, 132, intermediate shafts 131, 133 to the shafts 93^a that terminate in the borers 93. The cutters may be detached 30 and substituted by newly sharpened ones.

On the shaft 134 a worm 135 is provided engaging the worm wheel 136 fixed on the vertical shaft 137 that is adapted to be extended in the same way, and for the same 40 purpose, as described in connection with vertical shaft 126. For each of the plates 96, 96^a, 96^b, 96^c, two cam disks 138 are provided on shaft 137 which cam disks engage guide rollers 139 connected to oscillating plates 95. 45 The latter are rotatably mounted with their tapering ends at 141, and are guided while performing their oscillating movements by guide bars 140. They are connected to the frame of the machine by helical springs 142 50 that pull the plates 95 against the cam disks 138. While the plates 95 are advancing into the bore holes they break by their oscillating movement the coal off the bed.

The underground mining machinery, as 55 hereinbefore described, that makes it possible for mine works to change from hand labor to mechanically working the mine, means an extraordinary technical advance especially for the reason because mining work may now 60 be concentrated upon a small area. That facilitates and economizes getting the coal and keeping open and airing the mine. Besides, the work of gaining coal may at times be reduced or stopped entirely, or very much 65 increased without meeting difficulties. Work-

men must either be fully employed, or must be discharged. A machinery plant may run just to meet the requirements, or a second plant may be installed, in order to enable the colliery to adjust itself easily to the changing demand of the market. Moreover, the necessity to pile large and costly stores of coal will be removed by the machinery according to this invention.

Obviously parts of this machinery for underground mining may be modified without departing from the spirit of my invention, so I do not wish to be limited to details of construction.

What I claim, and desire to secure by Letters Patent of the United States, is:—

1. Mining machinery, especially for under-ground coal mining, comprising a mechanically movable frame work guiding an automatic coal cutting and breaking machine along the face of the coal seam, a traveling belt arranged on the side of the movable frame work, a coal spout beneath the discharge of the traveling belt, said spout being connected to the movable frame work, a drum on the head of the movable frame work, around which drum a steel rope is passed that draws, on one side of the movable frame work, the automatic coal cutting and breaking machine along the seam face, and is connected to a counterweight sliding on rails provided on the opposite side of the movable frame work, an automatic coal cutting and breaking machine provided with means for moving the machine, for driving the cutting and breaking mechanism, and for moving the coal broken on to the traveling bed, an inclined plate between the automatic coal cutting and breaking machine, and the traveling belt, said plate being connected to the movable frame work, means on the head end of the frame work for operating the drum, means on the foot end of the movable frame work for operating the coal conveyer, and the mechanism by means of which the movable frame work is moved in the line of the strike, whereby the said other parts of the machinery move with the frame work, substantially as described.

2. Mining machinery for underground mining, comprising in combination with an automatic coal cutting and breaking machine, with a coal conveyer and a coal spout, a mechanically movable frame work hanging by means of truckles on a girder that extends along the upper gangway of the mine, the frame work consisting of two rows of extending mining columns being connected, one with the other, by a flat-iron lattice-work arranged near the feet of the columns, said columns carrying on extending screw heads longitudinal and cross beams covered with sheeting boards held in position by elastic clamps, said screw heads being for the purpose of extending or lowering them,

mechanically operated, by means of worm gears, from two longitudinally extending power driven shafts, said columns being provided at their feet with wheels, the axles of which are mounted in yokes which latter are slidably mounted in the tubular interiors of the columns and are placed under spring pressure in such a manner that the yoke with the wheel axle attached is pushed into the tubular column while the screw head of the latter is extended for the purpose of securing it between mine roof and floor, said wheels on one row of columns being operated, by means of worm gears, from a longitudinally extending power driven shaft, for the purpose of shifting the frame work sidewise, said shafts for mechanically extending or lowering the screw heads of the columns, and for causing the whole frame work to move, receiving their rotation from a motor driving the traveling belt and shaft mounted on the lower part of the frame work, substantially as described.

3. Mining machinery especially for underground coal mining, comprising a mechanically movable frame work guiding an automatic coal cutting and breaking machine along the seam face, a traveling belt arranged on the side of the movable frame work, a coal spout beneath the discharge of the traveling belt, said spout being connected to the movable frame work, controlling

means for operating the two shafts longitudinally extending along the upper part of the columns for the purpose of causing the screw heads of the columns to extend or to contract, and the one shaft extending along the lower part of the columns for the purpose of causing the frame work to move sidewise in the line of the strike, said controlling means consisting of a shaft receiving its power of rotation from a motor mounted on lateral projections of the movable frame work, said shaft carrying between two bearings a fixed gear wheel, and adapted to be displaced longitudinally in order to bring the gear wheel into engagement with different gear wheels mounted on intermediate shafts parallelly disposed with said shaft, to cause the drum of the traveling belt to work, or to turn the shafts for operating the screw heads of the columns in one direction or in the other as may be required, or to impart power of rotation to the shaft that causes the whole frame work to move, substantially as set forth.

In testimony whereof I have signed my name to this specification in the presence of two subscribing witnesses.

CONRAD WISSEMANN. [L. S.]
